Design of
Air tight Cannon Stove.

Patented April 25, 1854.

Figure 2.

Dec. 642

Garrettson Smith & Henry Brown,
of Philadelphia, Pa.

Letters Patent No. 642-Dated April 25th, 1834.

The schedule referred to in these letters patent, and making part of the same.

To all whom it may concern:

Be it known that we, Garrettson Smith & Henry Brown, of the City and County of Philadelphia, and State of Pennsylvania, have invented or produced a new and original design for air-tight cannon stove, and we do hereby declare that the following is a full and clear description of the same; reference being had to the annexed drawing part of this specification, in which

Figure 1 is a front elevation of the stove.

Figure 2 is a front elevation of the foot, as seen when in position.

Similar characters of reference in the several figures denote the same part.

The ornamental design of this stove consists in the configuration of the open casing surrounding the fire cylinder, and in the bas-reliefs on the base and cylinder.

The casing A, is made up of the entwined foliage arranged and having the configuration set forth in figure 1 of the drawing. It is surmounted by the overhanging rim B, bearing the ornament in bas-relief b, c, and having its lower edge, as shown in the drawing.

The door D, is of the bottle form having two bottle panels C, and its upper portion ornamented, as shown in the drawing. Above and below the frame are the ornaments e and f in bas-relief, arranged and having the configuration set forth in figure 1.

The cylinder E, is surmounted by the rim F, and open dome F, formed, arranged, and ornamented as shown in the drawing.

The base G bears the projections f and h, is overhung by the rim H, and has the front of its hearth curved and embellished with the projections i. On the upper portion of the base is the fluted rim m, containing the grate. The projections and other ornaments of this portion of the stove are arranged as set forth in the drawing.

The foot P, has the configuration, and bears the ornaments in bas-relief shown and set forth in figure 2.

Symmetrical embellishments have but one half of their details shown in the drawing.

What we claim as our invention or production and desire to secure by Letters Patent, is

The design, configuration, & arrangement of the several ornaments in bas-relief, as herein described and set forth in the annexed drawing, forming a new & original design for an air tight cannon stove.

In testimony whereof, we have hereunto signed our names before two subscribing witnesses.
